UNITED STATES PATENT OFFICE.

SYDNEY HARRY SHERWOOD, OF BIRMINGHAM, ENGLAND.

OIL-LAMP.

1,149,091.

Specification of Letters Patent. Patented Aug. 3, 1915.

Application filed April 14, 1914. Serial No. 831,799.

To all whom it may concern:

Be it known that I, SYDNEY HARRY SHERWOOD, subject of the King of Great Britain, residing at 44 to 50 Granville street, in the city of Birmingham, England, have invented certain new and useful Improvements in Oil-Lamps, of which the following is a specification.

The invention relates to an oil lamp internally fed by ascending gentle air currents induced by a small fan applied internally to the base of the lamp, and driven by a wound-up spring. In such a lamp the oil container is surrounded by an outer shell between which and said container a free annular space is left for the flow of air from the inclosed base of the shell to within the burner cone. The burner of such a lamp is built up of three principle parts, burner body, burner cone, and globe or shade holder.

To this kind of oil lamp the invention solely relates, and provides the hereinafter built up of three principal parts, burner parts formed, and fitting each other, and the oil container, and inclosing shell, in a special manner, with the primary object of efficiently supporting the globe or shade holder, and at the same time enabling the trimming 30 of the wick to be easily performed.

The invention comprising said combination of parts is represented by the accompanying drawings.

Figure 1 is a vertical section of the complete lamp. Fig. 2 is a horizontal section of Fig. 1 on the dotted lines A B. Fig. 3 is a similar section as Fig. 1, but with the burner parts of the lamp separated from the oil container and shell body. Fig. 4 is 40 a plan of the lower burner piece Fig. 3.

The shell of the lamp, comprising base a, waist c, and body d, incloses and supports a fan mechanism, e, and the oil container, f, in the ordinary way, so that gentle air currents, induced by the fan e, flow upwardly and around the annular space g, between the body and oil container, in the manner indicated by the arrows, to feed the burner. The mouth of the oil container f is internally screw-threaded as at f², and between this mouth and the body of the shell is the annular outlet g² from the space g.

The foregoing construction of parts is well known in a lamp of the kind to which 55 the invention refers.

The invention combines with the screw-threaded mouth f² and the annular outlet g², aforesaid, and with a boundary rim g³ of said outlet, a burner h, a globe or shade holder i made integral with said burner, and a burner cone x made detachable in respect of said burner and globe or shade holder. The burner h carries the wick tube h² and the wick winder h³, and is formed at h⁴ with an externally screw-threaded shank to engage the screw-threaded mouth f² of the oil container f. The globe or shade holder i, within which the globe or shade may seat itself at y, or upon which said globe or shade may be otherwise supported, is formed at i² with a depending annular skirting, and is rigidly connected to the burner h by a plate-like part i⁴ freely perforated at i³. When the shank h⁴ engages the mouth f² of the oil container the annular skirting i² fits 75 over the annular rim g³, so that the outlet g² from the free space g feeds the gentle air currents from the fan e through the perforations i³. The globe or shade holder i being rigidly connected to the burner h, which 80 by the screw engagement h⁴ f² is most effectively attached to the oil container f, forms a most efficient support for the globe or shade no matter what its size or weight may be; the continuity of the air passages to the wick tube being at the same time maintained by the perforated plate i⁴ and the annular skirting i².

The burner cone x is formed at x² with a depending annular rim and at x³ with opposite gaps. The latter engage the stem of the wick winder h³ to aline the slot x⁴ of the burner cone with the wick tube, while the rim x² fits tightly within a shallow socket y² of the globe or shade holder i in the manner represented by Fig. 1, this tight fitting sufficiently holding the cone x in position upon the globe or shade holder so as to surround the wick tube h².

By the removal of the cone x from the integral burner h and globe or shade holder i the wick of the lamp can be trimmed: by screwing off the combined burner h and globe holder i the oil container f can be filled.

As hereinbefore stated the object of the invention is the rigid support of the globe or shade holder i by the combination of parts in a lamp of the kind to which the invention solely relates.

Having now described my invention what I claim and desire to secure by Letters Patent is:—

The combination with an oil lamp having an oil well and an outer shell surrounding the well and in coaction therewith defining an annular air passage concentric to the well and having an annular outlet at the adjoining upper ends of the well and the shell, of a burner comprising a burner body having a wick tube and formed for engagement in the upper end of the well, an annular globe holding rim concentrically circumscribing the body, a plate integrally connecting the rim and the body arranged below the plane of the rim to provide in conjunction with the said rim and body a socket concentric to the body, the plate alin-

ing with the outlet of the said air passage and having apertures formed therein through which the air flows from said passage, an annular flange integral with the rim and depending from the outer annular wall of said socket, the said flange being formed for engagement with the upper end of said shell and a burner cone inclosing the burner body and formed for detachable engagement with the outer annular wall of said socket.

In testimony whereof I have hereunto set my hand in presence of two subscribing witnesses.

SYDNEY HARRY SHERWOOD.
